UNITED STATES PATENT OFFICE.

WILLIAM F. DESTER, OF NEWARK, NEW JERSEY, ASSIGNOR TO U. S. TOOL CO., INC., OF EAST ORANGE, NEW JERSEY, A CORPORATION OF NEW JERSEY.

SAFETY LIGHTER FOR GAS STOVES.

Application filed July 11, 1925. Serial No. 42,871.

This invention relates to devices for lighting the burners of a gas stove, such as commonly used for cooking and heating purposes.

5 Stoves of this type ordinarily include a plurality of burners, each having an independent connection with a supply pipe or heater common to all, and being provided with a control cock, usually furnished with 10 an extending handle lever.

Ignition is generally accomplished by means of a small but constantly burning gas flame, called a pilot, disposed centrally among the burners, and adapted to direct a 15 jet of flame over the burners, upon the application of pressure to a push button valve, causing whichever burner to light that has been opened by its control lever.

Thus two distinct operations are required, 20 first, to open one or more of the lever controlled burner valves, and second, to press the pilot valve, holding it open until the burner or burners have become ignited.

The burner valves are ordinarily loosely 25 fitted and occasionally they become inadvertently opened partially or wholly, by the brushing of garments, mischievousness of children, or other causes, such occurrences being highly dangerous because of the emissions of gas into a room and consequences 30 of inhaling the same, the possibilities of an explosion and in any event the loss of gas thus escaping.

It is therefore one of the objects of the 35 present invention to provide a lighting means for the burners that operates automatically upon opening the burner cock, the pilot light being untouched.

It is a further feature to produce an igniting device that may be applied to any gas 40 stove of ordinary construction without material change therein, permitting its installation in old stoves as well as new.

These aims and objects, which will become 45 more apparent as the description progresses, are accomplished by the novel arrangement of parts hereinafter described and illustrated in the accompanying drawing, in which:—

Figure 1 is a top plan view of a conventional type of gas stove, the cover grill being omitted over half the area, showing the relative position of the burners and illustrating the application of the improved lighting means.

50 Figure 2 is an enlarged sectional view of

a burner and lighting device made in accordance with the invention.

Figure 3 is a partial side elevational, 60 partial sectional view of a modified form of igniter as applied to a burner.

In the drawing the numeral 5 designates generally the frame of a stove surrounding its upper portion, the same having an interior flange 6, arranged in a lower plane, to receive the removable cover 7, usually presenting a cross barred grating or grill and having circular openings 8 directly above the burners 9.

These burners, which may vary in size, 70 shape, number and disposition, are supplied with gas through tubes 10 leading outwardly through the front of the stove to air mixing bells 11, disposed in spaced relation in a level plane and provided with means to control the entering air as usual.

A header 12, connected with any convenient source of gas supply, is held in fixed relation to the front of the stove by supports 13 and provided with a series of cocks 14, 80 controlling the passage of gas to branch nipples 15, one for each of the inlet bells 11, the cocks usually being supplied with lever handles 16, each of which, upon being given a quarter turn, admit gas to the burner with which it is associated.

In the ordinary construction of gas stoves a pilot light is arranged at a point substantially equidistant between the several burners, this being supplied with a small quantity of gas and remaining constantly lit, the 90 consummation of gas being negligible, lighting being accomplished by a piston valve, which upon being opened, causes flames to issue from the pilot directed towards each of the several burners.

95 In the instant arrangement, a small pipe 17, provided with an adjustable control device 17', communicates with the header 12 and leads to a casing 18, being secured in its bottom wall 19, as shown in Figure 2, this 100 casing being supported in the stove by any suitable means, below the cover 7.

A burner 20, at the end of the pipe 17, supplies a fine jet of gas within the casing, the products of combustion escaping through 105 the perforations 21 in the top of the casing, which is provided with a plurality of bosses 22, one for each of the stove burners.

Engaged in each boss 22 is a small tube 23 bent at a right angle downwardly at the 110

center of each burner and communicating with an open, inverted cup 25 disposed above the center of the burner.

In operation, the pilot burner 20 being lit, the cock 14 of any desired burner 9 is opened, permitting gas, with a proper proportion of air, to enter the burner, whereupon a portion of the same will rise and be gathered in the cup 25 to be conducted through the tube 23 to the casing 18 and flame therein.

Immediately the gas entering by the tube 23 is ignited and the flame conducted back through the same pipe to the opened stove burner, causing the same to light almost simultaneously with opening the cock, the pilot remaining lit for further service.

From the foregoing it will be seen that the loss of gas is reduced to a minimum amount, that each burner as it is opened, whether intentionally or accidentally, becomes instantly lit, and that danger of escaping gas is thus avoided.

In the modification shown in Figure 3, the stove cover 7 is arranged relatively lower with respect to the burner 9 and in the opening 8 is an inverted flanged cup, its flange 31 resting on the cover as shown.

Connecting with the periphery of the cup 30 is a flexible tube 32 engaging in one of the openings 22 of the pilot casing, the arrangement being such that the igniting cup may be readily removed and swung out of the way, due to the flexibility of the tube 32, when desired.

From the foregoing it will be seen that a

simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent, is:—

1. A gas stove burner lighting device comprising in combination with a supply pipe leading to the burner, said burner having imperforate side walls and vertical discharge openings in the upper wall, and a cock controlling the pipe, of a pilot light having a constant supply of gas, a casing enveloping the pilot, said casing having a top, a shallow inverted cylindrical cup over the burner, at the center thereof and a tube communicating between said cup and the pilot chamber.

2. The combination with a gas stove having one or more burners provided with controllable gas inlets, and a cover having a substantially circular opening over each burner, said burner having vertical discharge openings and imperforate side walls of a pilot casing containing a constantly lit gas jet, an inverted shallow cylindrical cup over each of said burners, and a hollow connection between said pilot casing and inverted cup.

This specification signed and witnessed this 10th day of July, 1925.

WILLIAM F. DESTER.
